ATTORNEYS.

UNITED STATES PATENT OFFICE.

ALBERT L. ANDERSON, OF ROCKDALE, WISCONSIN.

RADIATOR.

Application filed June 4, 1920, Serial No. 336,618. Renewed April 13, 1922. Serial No. 555,229.

To all whom it may concern:

Be it known that I, ALBERT L. ANDERSON, a citizen of the United States, residing at Rockdale, in the county of Dane and State 5 of Wisconsin, have invented new and useful Improvements in Radiators, of which the following is a specification.

This invention relates to radiators for automobiles and other motor vehicles, its object being to provide a radiator which is in sections which are so connected that any section may be cut off from the others, and the sections are so assembled and connected that repairs can be easily made.

Other objects and advantages of the invention will be pointed out in the detailed description appearing hereinafter, and in order that the invention may be better understood, reference is had to the accompanying 20 drawing forming a part of this specification.

In the drawing,

Figure 1 is a transverse section of a radiator constructed in accordance with the present invention;

Fig. 2 is a horizontal section on the line 25 2-2 of Fig. 1;

Fig. 3 is a detail in perspective;

Fig. 4 is a front elevation of the radiator showing the same equipped with a shield, 30 and

Fig. 5 shows a different type of shield.

Referring specifically to the drawing, the radiator has the usual spaced top and bottom tanks 5 and 6, respectively, between 35 which are located water circulating tubes 7 arranged in a manner to be presently described. The tank top has a filler neck 8 provided with a removable closure 9, and an inlet for the heated water from the water jacket of the motor is shown at 10. The bottom tank has an outlet 11 through which the cooled water flows back to the water jacket.

The top and bottom tanks 5 and 6 are 45 connected by a central pipe 12 suitably connected to said tanks to open thereinto. This pipe provides a direct passageway of water from the top to the bottom tank, and the flow through the pipe may be shut off by a 50 valve 13 interposed therein, and located near the upper end of the pipe.

On each side of the pipe 12 is located a bank of water-circulating tubes 7 extending back and forth between said pipe and the 55 radiator end in a zigzag manner. Near the top of the pipe 12, the latter is provided with

a side branch pipe or nipple 14 carrying a manifold 15 having branches 16 to which the tubes 7 are connected at their upper ends, ordinary unions 17 being provided for 60 this purpose. The lower ends of the tubes are connected to the pipe 12 in the same manner as their upper ends. The top and bottom connections of the tubes 7 are provided with valves 18 the same being located in the pipe 14, so that all of the tubes on either or both sides of the pipe 12 may be cut off from the latter. It will therefore be seen that if any of the tubes on either side of the pipe 12 require repairs, they 65 70 can be removed after shutting the valves 18 on that side. In cold weather when the tubes on one side would be sufficient to cool the water, the circulation through one set of tubes may be cut off by closing the valves 75 of that set; or both sets may be cut out, leaving the water to circulate through the pipe 12 only, with the valve 13 thereof open of course.

The front ends of the manifolds are closed 80 by removable caps 19, which latter, when they are removed permit the tubes 7 to be drained when the valves 18 are closed, without the escape of water from the tanks 5 and 6, and the pipe 12, so that the radiator 85 may be continued in use, the circulation between the tanks being now through the pipe 12. The slant of the tubes 7 assists the circulation therethrough, and also makes them 90 easy to drain.

The tubes 7 are held in place by hollow rods 20 passing through the bends thereof. These rods pass through and are secured to spaced front and rear flanges 21 of plates 22, extending between the tanks 5 and 6, 95 and bolted, riveted or otherwise secured to flanges 23 on said tanks as clearly shown in Fig. 1. One of these plates is located at each end of the radiator, and there is also a plate on each side of the pipe 12. The 100 rods 20 are removable from the flanges 21 and hence the tubes 7 can be readily removed from the radiator after unscrewing the unions 17.

On the rods 20 are mounted spacers for 105 the tubes 7, the same being plates 23 having an aperture 24 through which the rods pass. Each bend of a tube seats between two of the plates 23 and the contiguous faces of the latter have grooves 24^a to seat said bends. 110

The large volume of water circulating through the pipe 12 between the tanks 5

and 6 reduces the liability of freezing to a minimum, and as no soldered joints are used, the radiator will not leak.

Fig. 4 shows the front of the radiator equipped with a pair of shields 25, one on each side of its vertical center line, and in front of the tubes 7. These shields are designed for use in extremely cold weather to shield the tubes 7 from direct exposure to the air, and thus prevent the water from getting too cool for the proper operation of the motor. The shields may be plain sheet metal plates as shown in Fig. 4, or perforated plates 26 as shown in Fig. 5 may be provided. In either case, the plates are held in place by the inner edges of the flanges 21, said edges being scalloped, and offset outwardly as shown at 27 to form slideways seating the vertical edges of the plates.

I claim:

1. A radiator comprising top and bottom tanks, a central circulating pipe between the tanks, a bank of circulating tubes on each side of the central pipe, and having a valved connection therewith, and a valve in the central pipe.

2. A radiator comprising top and bottom tanks, a central circulating pipe between the tanks, top and bottom manifolds on opposite sides of the central pipe and having valved connections with said pipe, circulating tubes connected at their ends to the top

and bottom manifolds respectively, and a valve in the central pipe.

3. A radiator comprising top and bottom tanks, a valved central circulating pipe between the tanks, top and bottom manifolds on opposite sides of the central pipe and having valved connections with said pipe, circulating tubes connected at their ends to the top and bottom manifolds respectively, said tubes extending in a zigzag manner between the central pipe and the radiator end, rods around which the bends in the tubes extend, and supporting means for the rods comprising plates secured to and extending between the tanks and having flanges to seat the rods.

4. A radiator comprising top and bottom tanks, a valved central circulating pipe between the tanks, top and bottom manifolds on opposite sides of the central pipe and having valved connections with said pipe, circulating tubes detachably connected at their ends to the top and bottom manifolds, respectively, said tubes extending in a zigzag manner between the central pipe and the radiator end, rods around which the bends in the tubes extend, and supporting means for the rods comprising plates secured to and extending between the tanks and having flanges to removably seat the rods.

In testimony whereof I affix my signature.

ALBERT L. ANDERSON.
